UNITED STATES PATENT OFFICE.

BURDETT LOOMIS, OF HARTFORD, CONNECTICUT.

PROCESS OF AND APPARATUS FOR THE MANUFACTURE OF GAS.

SPECIFICATION forming part of Letters Patent No. 404,205, dated May 28, 1889.

Application filed February 18, 1887. Serial No. 228,095. (No model.)

To all whom it may concern:

Be it known that I, BURDETT LOOMIS, a citizen of the United States, residing at Hartford, in the county of Hartford and State of Connecticut, have invented certain new and useful Improvements in Process of and Apparatus for the Manufacture of Gas; and I do hereby declare the following to be a full, clear, and exact description of the invention, such as will enable others skilled in the art to which it appertains to make and use the same.

This invention relates to the manufacture of illuminating and heating gas in cupola generating-furnaces, and embraces certain improvements in the process and apparatus, whereby the hydrocarbon vapors given off from fresh charges of bituminous coal or slack may be better converted into fixed gas by passage through heated fuel before escaping from the generator, and whereby hydrocarbon oil—such as naphtha—is better vaporized and mingled with water-gas in retorts or vaporizing-chambers at a moderate temperature before exposure to the high heat of the fixing-chamber, so that loss and waste of oil heretofore experienced by its destructive decomposition and the consequent formation of lamp-black and hard carbon is prevented and the manufacture of gas thus cheapened and improved, and whereby the apparatus is simplified in construction, made more compact, and can be more conveniently and effectually operated at comparatively small expense. My cupola generator is made double—that is, with two fuel and decomposing chambers and two superheating and fixing chambers in one shell, so connected by pipes and valves that each set, composed of a fuel-chamber and a superheating and fixing chamber, can be operated separately, or the two sets can be operated together as one apparatus for manufacturing gas. The cupola is provided with suitable supply-pipes for air and steam and with take-off pipes leading from its top and bottom, so that air or steam can be passed up or down through the fuel as its varying conditions require and products of combustion or gas can be passed off either at its top or bottom.

The matter constituting my invention will be defined in the claims.

The details of construction and operation

will be fully described with reference to the accompanying drawings, in which—

Figure 1 represents a vertical section from front to back of the cupola generator and the boiler, partly in elevation and partly in section. Fig. 2 represents a vertical section from side to side at right angles to the section in Fig. 1. Fig. 3 represents a rear elevation with the valve boxes and pipes partly in section. Fig. 4 represents a horizontal section through the cupola above the grates and a top plan view of the boiler and connecting-pipes and the condenser and scrubber. Fig. 5 represents a horizontal section of the double boiler.

The cupola generator A is built of brick, with a lining of fire-brick and an inclosing iron jacket, which is tightly riveted in the usual manner. A central vertical fire-brick partition, Y, having incased within the brick to the tight iron plate y, which is riveted to the outer iron jacket, divides the cupola from front to back, as shown in Figs. 2 and 5, and the horizontal brick partition W divides it across, forming at top the two fuel-chambers B B' and at bottom the two superheating and fixing chambers C C'. The grates b b of the fuel-chambers are formed of deep fire-clay bars, which taper from top to bottom and rest directly upon the partition or floor W. These grates thus arranged have been found most satisfactory in practice, since iron ones too quickly burn out and fire-clay bars break readily if not supported as here shown. An opening, X', and door x' are provided in each chamber for giving access to clean out the ashes between the bars. Side openings, X X, having doors x x, Fig. 2, are provided above the grates for convenience in kindling the fires and removing clinker. Fuel-supply openings b' b', having tightly-closing lids a a, are provided at the tops of chambers B B'.

The steam-superheating and gas-fixing chambers C C' are, for convenience and efficiency, arranged in the base or lower half of the cupola. The main fire-brick partition c' at one side forms flue C', connecting chambers B and C for the passage of superheated steam up into the fuel, or gas down into the fixing-chamber, and an opening, u, in the bottom of this partition leads from the flue into chamber C. In order to provide an effective and

convenient heating-surface, chambers C C' are provided with vertical fire-brick partitions *c c*, extending alternately from top and bottom, nearly the height of the chamber and 5 at the proper distance apart to form vertical connecting passages or flues. The partitions resting upon the bottom rise to within a distance of two to five inches from the top of the chamber, and the partitions extending from 10 the top project to within a similar distance from the bottom of the chamber, thus providing passage-ways alternately at top and bottom and between the partitions. When laying up the partitions, the oil-vaporizing 15 chambers or retorts D D' are set in position extending transversely through chambers C C' and the contained partitions, and opening into passage-ways C³. Two or more retorts may be set in each chamber, and two, as 20 shown, will usually be sufficient. Their outer projecting ends are closed with tight-fitting lids *d*, and with such ends the oil-supply pipes N N', having valves *n n'*, are connected. Pipes *k*, for supplying water-gas, also connect 25 with the ends of the retorts. A gas-take-off pipe leads from each fuel-chamber and each superheating and fixing chamber, so that gas or products of combustion can be passed off in either direction. Pipes F F' connect the 30 bases of chambers C C' with the base of the vertical steam-boiler E, one pipe connecting on each side of the vertical partition of the boiler. The gas-take-off pipes of the fuel-chambers are peculiarly arranged and connected, whereby important results are secured, 35 as described below.

At a distance about one-third the height of each fuel-chamber, below its top, a circular horizontal flue, P, is provided in the brick-work, and is connected with the interior of 40 the chamber by numerous short ducts or ports *p*, inclined downward, as shown, so that fuel will not lodge in them. In operating with bituminous coal for the manufacture of gas 45 in a cupola furnace it has been found quite advantageous to conduct off the gases below the surface of the fuel, and the latter is therefore maintained at a height of from ten to twenty-five or thirty inches above the ports 50 *p*. By this arrangement the condensable tarry vapors distilled from fresh charges of bituminous coal are compelled to pass down into the heated fuel below, and are thus converted into fixed gas. Another important 55 advantage arising from this arrangement and method of operating is that the coal is not baked at the top into a hard crust or arch, since the hot water-gas arising from the incandescent fuel below does not pass through 60 the fresh charges, and the latter are therefore distilled at a more moderate heat, so as to produce good coke.

Where the hot water-gas has been passed off directly through the fresh fuel the heat was 65 so high as to melt the coal and cause it to run together into coherent cakes, which retarded the flow of gas and passage of air, and other-

wise interfered with the operation of the generator. By my present improvements I overcome these difficulties and secure much better 70 results. Gas-eduction pipes G G' lead from flues P at the rear of the cupola and connect with the vertical pipes II II', which connect below with pipes F F', as shown in Figs. 1 and 3. Pipes I I' extend above pipes G G' 75 and connect them with a hydraulic seal-box. (Not here shown, but which is arranged in a well-known manner to seal the ends of the pipes in a liquid.) A short pipe, *g*, connects pipes I I', for conducting gas from one fuel-chamber to the other when the valves are 80 properly adjusted.

Valve-boxes U U', having large openings closed by lids *w*, are placed at the junctures of the pipes G II I and of the pipes G' II' I', 85 and are provided with upper seats, *r'*, and lower seats, *s*, to accommodate the ball-valves *h h'*. Each ball-valve is suitably hung upon a lever-arm attached to a rock-shaft which passes through the casing, and is provided 90 externally with an operating-handle, so that the valves can be raised or lowered upon either seat, as desired. Similar valve-boxes V V', having openings closed by lids *v*, are bolted to and connect the pipes F H and the 95 pipes F' H', and are provided with seats *a' e'* and with ball-valves *f f'*, hung and operated like those above described.

A pipe, K, having valve *i*, leads from each of the pipes G G' and connects by means of 100 branch pipes *k* with retorts D D' for supplying them with hot water-gas. Steam-pipes may also connect with the retorts or with injecting-nozzles, to which the oil-supply pipes N are also connected for injecting and spraying the oil. The gas-inlet pipes may also be connected to such nozzle. Steam-supply pipes J J', having valves *j j'*, connect with the pipes F F' for supplying steam to the bases of chambers C C'. Pipes L supply steam direct to 110 the fuel-chamber, one branch, L', having valve *l* connecting with flue P, and one branch, L'', having valve *l'* connecting with the lower part of the chamber above the grate. 115

Air-blast pipes connect with the tops of the 120 fuel-chambers and with the superheating and fixing chambers through the medium of chamber T and vertical flue C³. The main air-blast pipe R leads from the blower Q, and branch pipes R' extend up at the sides of the 125 cupola and connect by short branch pipes *m m*, having valves *r*, with the tops of the fuel-chambers, and by short branch pipes *o*, having valves *t*, with flues or chambers T, formed in the brick walls at the fronts of 130 chambers C C'. Numerous small ports *t'* inclined downward open from chamber T into vertical flues C³, so that numerous fine streams of air may be mingled with and cause complete combustion of hot gaseous products 135 passing down from the fuel at the time of heating up the chambers. The boiler E is divided into two chambers, *e e*, by a vertical division-plate, as shown in Fig. 5, and inlet-

pipes F F' connect one with each chamber, and outlet-pipes M M' at the top also connect one with each chamber and extend into the hydraulic seal-box P'.

5 Pipes O O' rise from pipes M M' and open at top into the usual stack-pipe. They are provided at top with ball-valves o', having suitable operating-levers. When the valves are open, products of combustion escape into the stack; but when they are closed gas passes through pipes M M' into the seal-box. Since the ends of pipes M M' are sealed by liquid in the box, the resistance is sufficient to prevent the flow of products of combustion in that direction when valves o' are open, and also to prevent the escape of gas by back-pressure; but when valves o' are closed gas passes from pipes M M' through the liquid seal in the usual manner. A steam dome or 15 drum, S, connects with the top of the boiler. An oil-pump, N'', and elevated tank O'' supply oil to the vaporizing-retorts. Openings 20 z z, Fig. 2, having tight-fitting caps, are formed in the walls at the bases of the chambers C 25 C' for removing soot and ashes from between the partitions c c.

In order to make illuminating-gas, all the chambers of the cupola are preferably operated together, as follows: The lids a being re- 30 moved, fires are kindled on the grates and at first allowed to burn by natural draft. Coal or coke is gradually fed in till deep beds of fuel are formed and well ignited. Then all 35 the lids and doors of the cupola are closed, valves f f' raised upon seats e' e', and valves h h' dropped upon seats s and stack-valves o' both opened. Blasts of air from the blower are now admitted through valves r and pipes m and driven down through the fuel. When 40 combustible products are discharged from the fuel, air-blasts are admitted through pipes o and valves t into chambers T, from which it is distributed through ports t' to the hot gaseous products in flue C³, causing their com- 45 bustion, and the highly-heated products pass through chambers C C', imparting their heat to the brick partition-walls, and pass thence by way of pipes F F' into and up through the boiler and out of pipes O O' to the stack. 50 The blasts are continued till beds of fuel of sufficient depth are heated to incandescence, and chambers C C' are heated to the proper temperature for superheating steam and converting hydrocarbon vapors into a fixed gas. 55 The fuel should be heated to a temperature between 2,000° and 3,000° Fahrenheit, and the chamber C or C', which is to be used as the steam-superheater, should be heated to about 2,500° Fahrenheit, while the chamber 60 C or C', which is to be used for fixing gas, should be heated to a temperature between 1,200° and 1,800° Fahrenheit. The bodies of fuel and chambers C C', being properly heated, the air-blasts are shut off, stack-valves 65 o' are closed, valves h h' are dropped upon seats s s, and valve f' is dropped upon seat a', while valve f is retained upon the upper

seat, e' (see Fig. 3,) providing an open passage from chamber C through pipe F to the boiler and seal-box. Steam is now admitted through 70 pipe J' and pipe F' into the base of chamber C', through which it passes and becomes highly superheated; and in this condition passes directly up into the incandescent fuel in chamber B', where it is decomposed, forming wa- 75 ter-gas, which passes by ports p below the surface of the fuel into the flue P, and thence by pipes G', g, and G, flue P, and ports p into fuel-chamber B some distance below the surface of the fuel. In passing down through 80 the fuel in this chamber carbonic acid present in the gas is converted into carbonic oxide, and hydrocarbon vapors given off from the fresh charges of bituminous coal are converted into fixed gas. By this method of operating bituminous coal slack or dust can be successfully fed onto the fuel above ports p and there distilled, since the hot water-gas does not pass through and melt it and the hydrocarbon vapors evolved pass into the hot 85 fuel below and are converted into fixed gas. Good coke is thus produced, which descends in the chambers as the ash is removed below. By the use of bituminous coal much carbureted hydrogen or marsh-gas is produced, 90 which is a valuable addition to the water-gas. The mixture of water-gas and marsh-gas passes from chamber B down through the grate into chamber C, where it is carbureted and fixed. As gas passes from chamber B' 95 through pipe G, valve i in pipe K is opened and a regulated portion of gas is passed by pipe K and branches k into retorts D at the same time that regulated streams of hydro- 100 carbon oil are admitted to the retorts. The oil is vaporized and diffuses in the gas, and is carried thereby into flue C³, where it meets and carburets the gas passing down from the fuel. The carbureted gas passes through fix- 105 ing-chamber C, where it is combined and converted into a fixed gas, which passes through the boiler to the seal-box, from which it is conducted by pipe M'' to the condenser. (Not 110 shown.)

At the time gas is passed through the sec- 115 ond fuel-chamber B a limited supply of steam may be admitted by pipe L' into flue P and passed with the gas into the fuel and decomposed. This will be advantageous when the fuel is at a very high heat. The manufacture 120 of gas is continued as above described so long as the fuel and the fixing-chamber remain at the proper decomposing and converting tem- 125 perature. As soon as the beds of fuel and the chambers C C' are cooled below the proper working temperature the steam and oil are 130 shut off, the valves for escape of products of combustion are adjusted, as before described, and the air-blasts again admitted till the bodies of fuel and chambers C C' are again prop- erly heated. During the second gas-making run the direction of gas and steam through the chambers may be reversed—that is, the steam may be admitted to and superheated

in chamber C and the gas be carbureted and fixed in chamber C' and discharged from its base through pipe F'. Thus at each successive run the direction of the currents may be reversed or, if desired, the direction of the currents may be reversed during the run. By this method of operating carbon which may be deposited in the fixing-chamber during one run or period is taken up by the steam during a subsequent run or period and the chambers thus kept clean.

With the pipe-connections and valves shown, either set of chambers, as B C or B' C', can be operated separately for manufacturing gas, while the other set is being blasted with air. If heating-gas only is desired, valve f is closed down on seat a', and valve h is closed upon seat r after the fuel and superheating chambers have been heated, and steam is then superheated by passage through chamber C, and is decomposed in the fuel in chamber B, and the resulting gas is conducted off through pipes G, H, and F. Both sets of chambers may be operated in this way at the same time. Should it be desired to make illuminating-gas by the use of a separate set of chambers, they are first heated. Then valve f is raised against seat e', and valve h is raised against seat r', and steam is admitted into the upper part of the fuel through flue P, is decomposed by passage downward, and the resulting gas is carbureted in the fixing-chamber C, and is conducted off through pipe F. In this way one set of chambers, as B C, is used for making illuminating-gas, while the other set, as B' C', is being blasted with air and heated up; or both sets may be simultaneously blasted and heated up and independently used for making gas.

The bodies of fuel may be advantageously heated by forcing the air-blasts down into the fuel and discharging the products of combustion near the tops of the chambers, and can be accomplished by closing valve f upon lower seat, a', and raising valve h onto seat r', admitting the air-blast through pipe m, and forcing it down into the fuel, and permitting the products to rise and escape through ports p and flue P into pipe G, from which they pass through pipes H and F to the boiler. By this method the air penetrates down through the fuel and circulates upward, causing uniform combustion, and the products readily escape by way of ports p and flue P.

By means of the downward air-blasts ashes are blown down through the grate and the fuel is kept clean.

The vaporizing-retorts passed through the fixing-chambers afford increased carbureting-surface and prevent the too sudden exposure of the oil to the highly-heated brick, whereby waste by burning is prevented. The ball-valves afford great convenience and facility in operating the apparatus.

The apparatus is adapted for making either heating or illuminating gas under a variety of conditions.

Having described my invention, what I claim, and desire to secure by Letters Patent, is—

1. The process of manufacturing gas, which consists in superheating steam, then decomposing it in contact with a body of incandescent fuel, and at the same time distilling bituminous coal on top of and in contact with the body of incandescent fuel, and causing the resulting gas and vapors to pass downward through the distilling-coal into contact with the heated fuel below for converting them into fixed gas, and finally conducting off the coal-gas and the water-gas together, some distance below the surface of the distilling-coal and above the bed of the incandescent fuel, whereby fresh charges of bituminous coal are successfully coked and the hydrocarbons distilled therefrom converted into fixed gas without destructive decomposition.

2. The process of manufacturing gas, which consists in heating a body of fuel to incandescence by blasting with air, and by means of the resulting hot products heating a chamber containing refractory material, then shutting off the air and superheating steam in contact with the hot refractory material, decomposing it in contact with the incandescent fuel, and at the same time distilling bituminous coal in the form of lump or slack, in contact with the incandescent fuel, and causing the resulting gas and vapor to pass down through the distilling-coal into contact with the incandescent fuel for converting them into fixed gas, and finally conducting off the coal-gas and water-gas together below the more recent charge or charges of fresh coal and above the bed of incandescent fuel, whereby the coal is better coked, the formation of hard crusts by excessive heat of the water-gas is avoided, and the hydrocarbons are converted into fixed gas.

3. The process of manufacturing gas, which consists in heating two bodies of fuel to incandescence by blasting with air, burning the resulting gaseous products, and thereby heating two superheating and fixing chambers, superheating steam by passing it through one superheating-chamber, decomposing it by passage up through one body of incandescent fuel, and at the same time causing distillation of fresh charges of bituminous coal in contact with the bodies of incandescent fuel, and passing the evolved gas and vapor and water-gas from below the recently-charged coal into the second body of fuel below its surface and down through it for converting carbonic acid into carbonic oxide and hydrocarbons into fixed gas, then carbureting the mixed gas by means of hydrocarbon liquid, and finally combining and fixing the carbureted gas by passage through the heated fixing-chamber.

4. In a cupola gas-generating furnace, the fuel-chamber having a circular flue in its wall, eduction-ports opening therefrom into the

chamber, and a connected gas-take-off pipe arranged at a distance below its top and above its central portion, in combination with an air-blast pipe connecting with the top of 5 the furnace, and a steam-supply pipe connecting with the base of the fuel-chamber, for the purpose described.

5. In a cupola gas-generating furnace, the fuel-chamber having an air-blast pipe connecting with its top, and the gas-education pipe connecting below its top, as described, in combination with the superheating and fixing chamber placed at the base of the cupola, the connecting-flue C³ and vaporizing-retorts extending transversely through the superheating and fixing chamber and opening into flue C³, for the purpose described.

6. In combination with the fuel-chamber of a cupola gas-generator, the deep fire-clay 20 grate-bars resting upon the floor of the chamber, for the purpose described.

7. In a cupola gas-generating furnace, the superheating and fixing chamber having vertical partitions forming connecting-flues, and 25 the vaporizing-retorts extending transversely through the chamber and opening into a flue leading from the fuel-chamber, for the purpose described.

8. The two fuel-chambers connected by a 30 pipe or pipes for the passage of gas from one to the other, in combination with the two superheating and fixing chambers having the vaporizing-retorts, and the outside gas-inlet pipes, K k, leading from the connecting gas- 35 pipes of the fuel-chamber into the retorts for conducting water-gas to such retorts to mix with oil-vapor therein generated, all as described.

9. In a cupola gas-generator, the fuel-chamber 40 above and the connected superheating and fixing chamber below, in combination

with gas-take-off pipes G and F, connecting-pipe H, connecting valve-boxes U V, having seats at top and bottom, and the ball-valves suitably hung, so as to be adjustable upon 45 either seat, for the purpose described.

10. The combination of the two fuel-chambers and two superheating and fixing chambers connecting therewith, and the double steam-boiler, pipes, and valves connecting the 50 fuel-chambers with each other and with the chambers of the boiler, and pipes and valves connecting the superheating and fixing chambers with the chambers of the boiler, whereby either gas or products of combustion may be 55 passed through each chamber of the boiler, as described.

11. The two fuel-chambers and the two superheating and fixing chambers connecting with such fuel-chambers, in combination with 60 pipes F F', having valve-boxes and valves connecting the superheating and fixing chambers with the double boiler, pipes G, G', and g, and valve-boxes provided with double seats, and ball-valves connecting the two fuel-chambers, and the pipes H H' connecting pipes G 65 G' with pipes F F' through the medium of the valve-boxes.

12. The two fuel-chambers connected by a valved pipe or pipes below their tops and below the level at which the fuel is maintained, in combination with two superheating and fixing chambers having steam-supply pipes and valved take-off pipes for gas and products of combustion, as described. 70

In testimony whereof I affix my signature in presence of two witnesses.

BURDETT LOOMIS.
